CLAIM

The ornamental design for a chop saw, as shown and described.

DESCRIPTION

FIG. 1 is a front and right side perspective view of a chop saw showing my new design, the saw being shown in the raised position;

FIG. 2 is a front and left side perspective view thereof; FIG. 3 is a front and left side perspective view, the saw being shown in the lowered position;

FIG. 4 is a right side perspective view of FIG. 3;

FIG. 5 is a left side perspective view of FIG. 3;

FIG. 6 is a rear perspective view of FIG. 3.

The undisclosed bottom surface of the base portion of the chop saw is substantially plain and unornamented.

FIG. 5

FIG. 6
